UNITED STATES PATENT OFFICE.

HENRY GOODENOW, OF MONTROSE, WISCONSIN.

COMPOUND METAL-WORKING MACHINE.

SPECIFICATION forming part of Letters Patent No. 356,118, dated January 18, 1887.

Application filed June 1, 1886. Serial No. 203,852. (No model.)

To all whom it may concern:

Be it known that I, HENRY GOODENOW, a citizen of the United States, residing at Montrose, in the county of Dane and State of Wisconsin, have invented certain new and useful Improvements in Combined Punching, Shearing, and Tire-Shrinking Machines; and I do hereby declare the following to be a full, clear, and exact description of the invention, 5 such as will enable others skilled in the art to which it pertains to make and use the same.

My invention relates to an improvement in combined punching, shearing, and tire-shrinking machines, especially adapted for the use of blacksmiths, all as set forth in the following 15 specification.

Figure 1 is a side elevation of my combined machine. Fig. 4 is a transverse section of the same through the line $x-x$. Fig. 2 is a longitudinal vertical section through the machine on the line $y-y$ of Fig. 4. Fig. 3 is an end view of the machine as shown in Fig. 2. Fig. 5 is an elevation showing the relative position 20 of the parts on the tire-shrinking device when the hand-lever is up, as shown in Fig. 2.

In the drawings similar letters where they occur refer to like parts throughout the several views.

The frame-work of the machine may be either 30 of separate castings properly secured, or preferably, as shown in the drawings, it may be a single casting properly cored to admit the slide-bar and angle-lever, hereinafter described, the longitudinal central supporting- 35 rib being designated by B, and the respective vertical frame-pieces of said casting extending therefrom on either side of the same I designate, respectively, by A. The angle-lever L, pivoted at p , between the two upright portions 40 A A, extends through the whole length of the machine, its forward end projecting somewhat and being slotted to admit the hand-lever C, pivoted at its lower end to the forward-projecting end of the rib B, and operatively connected 45 with the angle-lever L by the links $l-l$, between which said links said hand-lever is adapted to pass freely. The knife a, bolted to the angle-lever L, and the knife b, similarly bolted to the rib B, are adapted to be operated as metal 50 shears—the forward or straight cutting-edges

for cutting sheet and plate metal, and the rear or curved edges for cutting rods.

In order to prevent the knife a and lever L from being deflected when cutting heavy work, I provide the lever L, at its forward end, with a guide-extension, g, fitting closely, but adapted to reciprocate freely between the opposite inner faces of the frame-castings A A. The rear lower arm of the angle-lever L also serves the same purpose to a considerable extent. 55 Between the inner vertical faces of the upper part of the frame-pieces A A, I insert the horizontal bar D, having a series of upward extensions, I, provided each with a metal punch, e, properly secured thereto, said bar being 60 adapted to reciprocate horizontally on the bolts d d, extending through the sides A A and the horizontal slots d' d' of the bar D. The punches e are preferably of different sizes, and may be either permanently set in the extensions I or so adjusted therein as to be removed 65 when so desired.

I do not restrict myself to any particular number of these punches, as it is obvious that the machine may be constructed with reference 70 to a greater or less number of them as desired. The work to be punched is placed against the face-plates or punch-blocks e, suitably pierced longitudinally to admit the forward end of the punch as it passes through the work and allow 75 it to force the waste material through and out of said longitudinal aperture.

The punch-blocks e may be bolted, dove-tailed, or fastened between the inner vertical faces of the frame-pieces A A in any usual manner, the latter being provided at proper intervals with suitable transverse slots, f, for receiving the work to be punched, the forward slot, f', being adapted to receive broader sheets than the others. The bar D is operatively connected 80 with the rear upward extension of the angle-lever L by means of the pivot-block E and tie-strap h, the lever L operating through the former to force the punches through their work and through the latter to retract them. 85 The pivot-block E, resting in curved seats in the rear end of the bar D and front face of the upward extension of the lever L, respectively, is held in position transversely by the tie-strap h. (See Fig. 1.)

The lower end of the arm F, pivoted to an extension on the upper forward end of the frame A, is operatively connected with the lower rear extension of the angle-lever L by means of the tie-rod R, and is further secured at its lower end by the headed guide-pin i, extending through the arc-slot j of the arm F into the central supporting-rib, B. By this means the arm F is prevented from deviating 10 transversely in the process of shrinking the tire. It is further provided with the curved seat m, rigidly secured to its outer face, and with the dog k pivoted to the same. The dog k' is similarly pivoted to the adjacent corresponding face of the frame A, which face is also provided with the curved seat m', rigidly fastened thereto.

The dogs k k' are constructed with wide steel chisel-edges sufficiently sharp to engage 20 readily and hold against the tire-surface. In the drawings the face of the dogs k k' is represented as upset, in order conveniently to obtain the transverse chisel-edges; but I make no claim to any particular form of dogs in this 25 connection. The dogs k k' are to be provided with hardened-steel ends, attached by welding or any other common device, and sharpened into comparatively wide transverse chisel-faces adapted to engage against and firmly 30 hold the tire in position to be shrunk.

It has been the custom in the class of tire-shrinkers herein described to use pivoted dogs having either toothed engaging-cams or comparatively narrow engaging-points. Neither 35 of these devices, however, is as effective in holding the tire from slipping as is my device, herein described, of providing each dog with a wide hardened-steel chisel-edge, which can be kept sharp more conveniently and at less 40 expense than can the edges of a toothed cam, and holds the tire in position much more firmly, and, after the tire has been properly shrunk, can be more conveniently disengaged therefrom. As a matter of practical construction for ordinary tire-shrinking, I prefer to 45 make said chisel-faces about two and one-half inches wide; but I do not wish to be understood as limiting myself to any particular width.

50 When the seat m is joined to the seat m', they together form the arc of a circle whose diameter will be about that of the average wheel-tire. The whole machine, as described, may be mounted on suitable standards or feet, 55 and can stand on the floor or the ground, and is adapted to be operated by hand.

The tire-shrinking device is operated as follows: The tire, having been sufficiently heated, is placed on the upper curved surfaces of the 60 seats m m'. (See Fig. 5.) The dogs k k' are then set firmly against the tire on its inner surface to hold it from slipping, the heated portion of the tire being between the engaging edges of the same. (See Fig. 1.) The operator 65 then bears down on the hand-lever C, which motion, by means of the links l l and angle-lever L, is communicated through the

tie-rod R, drawing the arm F, with the seat m, back against the seat m'. During this operation the tire, being held rigidly by the dogs k 70 k', is crowded or looped up at the heated portion, and thereby lessened in diameter or shrunk. While in this condition on the machine the loop or upset portion may be hammered smooth, so that when removed from the 75 machine the tire is ready to be set. It is obvious that the operative power originally applied to the end of the hand-lever C is multiplied through the links l l and angle-lever L. At the same time that the operating-lever C is 80 moved downward the lever L is drawn down, the knife a closing by the knife b, while the series of punches are pressed forward until their points enter the clearance-apertures.

I am aware that in tire-shrinking machines 85 devices are in use wherein the tire is held by dogs in a curved seat consisting of two sections, one section being fixed and the other being adapted to be moved up against the fixed section, thereby upsetting the tire between the 90 engaging points of the dogs. Such arrangement I do not claim, broadly; but

What I do claim, and desire to secure by Letters Patent from the United States, is—

1. In a combined punching, shearing, and 95 tire-shrinking machine, the hand-lever C, pivoted at its lower end to the central rib, B, provided with the knife b, in combination with the links l l and the angle-lever L, pivoted at its rear end between the inner vertical faces of 100 the frame-pieces A A, and provided with the knife a and forward guide-extension, g, whereby both metal plates or sheets and rods may be sheared or cut, respectively, all as set forth.

2. In a combined punching, shearing, and 105 tire-shrinking machine, the hand-lever C, pivoted at its lower end to the central rib, B, links l l, angle-lever L, pivoted at its rear end between the inner vertical faces of the frame-pieces A A, and having a rear upward-extending arm, the pivot-block E, tie-strap h, and slide-bar D, provided with the horizontal slots d' d', and the several upward extensions, I, bearing the punches c, in combination with the frame-pieces A A, provided with corresponding transverse slots, f' f', for admitting 115 the work to be punched and pierced, punch-blocks e, secured, as described, at proper intervals between said frame-pieces A A, whereby said slide-bar D, actuated by said angle-lever, pivot-block, and tie-strap, is adapted to reciprocate on the bolts d d', operating the punches c, substantially as described, and for 120 the uses and purposes mentioned.

3. In a combined punching, shearing, and 125 tire-shrinking machine, the hand-lever C, pivoted at its lower end to the central rib, B, the links l l, the angle-lever L, pivoted at its rear end between the inner vertical faces of the frame-pieces A A, and having a rear downward-extending arm, and the tie-rod R, in combination with the arm F, provided with the dog k and seat m, said arm being pivoted 130 at its upper end to the machine-frame and

provided at its lower end with the arc-slot *j*, adapted to reciprocate over the headed guide-pin *i*, extending from the central rib, *B*, whereby the arm *F* is prevented from deviating 5 transversely in the process of shrinking the tire, and the dog *k'*, pivoted to, and seat *m'*, rigidly fastened to, the adjacent corresponding face of the machine-frame, substantially as described, and for the purposes set forth.

In testimony whereof I have signed this to specification in the presence of two subscribing witnesses.

HENRY GOODENOW.
